UNITED STATES PATENT OFFICE.

JAMES F. STRUBLE, OF HUTCHINSON, KANSAS.

ANTIFREEZING DEVICE.

Application filed February 28, 1924. Serial No. 695,704.

This invention is an improvement in anti-freezing devices, and with respect to its more specific features, relates to devices applicable to the water circulation systems of motor vehicles.

In cold weather, impedance or stoppage of the water circulation in the cooling system is a fruitful source of trouble. The stoppage or impedance is due to freezing of the circulation water, and it usually commences in the return pipe from the radiator to the water jacket.

The said pipe is remote from the engine, and receives practically no heat therefrom, and it is subjected to the blast of the cooling fan, driving rearwardly and downwardly, directly over the pipe. In addition, the water holds less of heat when passing through this part of the system than in any other.

An object of the invention is to remove this source of trouble, and a feature of the invention is the provision of mechanism for raising the temperature of the cooling liquid in this part of the system above the freezing point, when climatic conditions are such as to make freezing probable.

With this and other objects in view, the invention consists in the construction and novel combination of parts fully described hereinafter, illustrated in the accompanying drawings, and pointed out in the appended claims; it being understood that various changes in the form, proportion, size and minor details of construction, within the scope of the claims, may be resorted to without departing from the spirit of the invention.

In the drawings forming a part hereof; Figure 1 is a side elevation of a part of a motor car provided with the improved device, with parts broken away;

Figure 2 is a plan view of a heater section;

Figure 3 is a similar view of an alternate arrangement.

The present embodiment of the invention is shown in connection with the water circulation system of a motor vehicle 1, the system including the radiator 2, at the front of the hood 3, and connected to the water jacket of the engine 4, by the usual circulation pipe, the return pipe being indicated at 5. Behind the radiator, and between it and the engine, is arranged the fan 6, for cooling the radiator. The pipe 5 is below and behind

the fan, and is subjected to the action of the blast driven thereby.

In order to prevent freezing of this pipe, at which point freezing is usually first to appear, I provide means for heating the pipe, from the point where it leaves the radiator to a sufficient distance to shield it from the blast of the fan. This heating means may be of any preferred form and character, and supplied with heat in any desired manner.

In the present instance I use a heater in the form of a sectional casing, composed of similar sections 7, each a half cylinder, and provided at one side edge with a marginal flange 8. At the opposite side edge the sections are hinged together, as indicated at 9, and the flanges 8 are connected in any suitable manner, as for instance by bolts and nuts 10.

With this arrangement, the heater may easily be attached or removed, and preferably the sections of the casing are lined with some non-heat conducting material, as for instance asbestos. The ends of the sections are formed to fit the pipe closely, as indicated at 11 and 12, respectively, and one of the sections is provided with inlet and outlet nipples 13 and 14, respectively, the former for connection with a pipe 15, which leads from the exhaust pipe manifold 16.

The heater casing may be of any suitable material, as for instance sheet metal of suitable weight, stamped or pressed to shape, or it may be in the form of a casting, and its shape will depend on the shape and location of the return pipe 5. If for instance the pipe is bent or curved, the heater casing may be similarly shaped.

The improved device not only prevents freezing when the engine is running, but affords a measure of protection for the pipe when the car is not in use. It provides a non-heat conducting jacket for the pipe at all times, and will retain heat for a considerable time after the engine ceases to run.

The exhaust gases flow from the manifold through the heater casing, and are discharged by the nipple 14, which extends through the dust pan 18, and delivers beneath the car. A valve 17 is provided in the pipe 15, by means of which the flow through the casing, and as a consequence the

amount of heat obtained, may be nicely regulated. When there is no probability of freezing, this valve may be closed, thus shutting off the flow of gases from the manifold. 5 The nipple 14 should be of sufficient capacity to give free vent to the exhaust gases passing through the casing when the valve is fully open.

10 The device as a whole is extremely simple, and it may be manufactured at a low cost. It is easily applied and removed, and requires no attention when once in place.

15 An alternate construction of heater casing is shown in Fig. 3, wherein the sections of the casing, one of which is indicated at 19, are provided with marginal flanges 20 at both side edges. The flanges have openings which register when the sections are in place, and the flanges are connected by bolts and 20 nuts 21. The bolts are passed through the openings and are engaged by the nuts, by

means of which the sections may be clamped on the pipe. The construction is otherwise the same as that of Fig. 1.

What I claim as new is:

25 An anti-freezing device for the return pipe of the water circulation system of an internal combustion engine, comprising a casing of a cross section and length to enclose and jacket the full length of the return pipe from the radiator to the engine, said casing composed of separable sections, and means to secure the sections together about the pipe to be wholly supported thereby, said casing having an inlet and an outlet 30 pipe for connection with the exhaust manifold of the engine and the atmosphere respectively, and a valve in connection with one of the pipes.

35 In testimony whereof I affix my signature.

JAMES F. STRUBLE.
